UNITED STATES PATENT OFFICE.

JOSEPH MAY, OF FRANKFORT-ON-THE-MAIN, GERMANY.

PEN CLEANER.

Application filed March 15, 1923. Serial No. 625,312.

To all whom it may concern:

Be it known that I, JOSEPH MAY, a citizen of the German Empire, residing at Frankfort-on-the-Main, Holzgraben 2, have invented certain new and useful Improvements in Pen Cleaners, of which the following is a full, clear, and exact description, reference being had to the accompanying drawing and to letters of reference marked thereon.

10 My invention relates to a new pen-cleaner. For pen-cleaners, material of different kinds for dry and wet use has heretofore been proposed; but these materials were not satisfactory for wiping the pens and did not accomplish their purposes. In some cases such materials clog the pens with fibres, in consequence of the fibrous nature of said material, or in the case of wet cleaners, a very speedy ruin of the pens by rust has resulted from their use. To the aforesaid class of dry wiping devices belong for example, felt, soft leather and the like while the class of wet wiping devices includes, for instance a sponge fitted in a water chamber.

15 20 25 The nature of the present invention consists in the use of a sponge-rubber for dry wiping of the pens.

For the purpose referred to, this material is fitted specially owing to its natural qualities. Sponge-rubber is smooth, soft, slippery and porous. It does not unravel, removes the ink and the residues smoothly and completely from the pen and does not suck up or absorb the ink, like felt, soft leather or other fibrous materials. The ink and the ink residues wiped from the pen are loosely accumulated upon the surface of the sponge-rubber and are therefore very easily washed out and removed thus making it easy to maintain the cleaner in a serviceable condition. In consequence of its smooth and slippery surface the sponge-rubber preserves the pens against undue wear in cleaning and wipes them completely dry. Moreover the sponge-rubber is further advantageous, because it does not clog the pens with fibres, which cause imperfections in subsequent writing with the aid of said pen.

50 The accompanying drawing shows two examples of the new pen-cleaner one of which is for use by hand and the other of which is capable of use by hand or as a standing pen-cleaner upon a writing table or desk. In said drawing—

55 Fig. 1 is a section of the pen cleaner for use by hand, and

Fig. 2 a top view thereof.

The pen-cleaner, in the form shown in Figs. 1 and 2, consists of two arched plate-shaped parts *a*, *a'*, each of which constitutes a body and are covered on the inside with sponge-rubber and which have their convex surfaces toward each other are held together by an elastic member. The annular slit formed in this manner for cleaning and wiping the pens may be compressed by the plate-shaped parts at any place, or may be caused to spread or gap at a point opposite to the point at which pressure is exerted to press the plate-shaped parts *a* and *a'* toward each other. The execution of the pressure results in an axial direction.

Instead of the central fastening means, a tension chain may be provided, which tension chain is stretched around the sponge-rubber so as to extend about the foot of the cupola. The body itself may be manufactured in any convenient manner and of every suitable material and it may simultaneously serve other purposes, for instance, as a letter-presser or the like; it may also be used for advertisements.

55 60 65 70 75 80 85 90 95 The yielding, universally pliant, soft and smooth slippery mass of the sponge-rubber, makes it possible to thoroughly clean the pens or the like with the least wear thereon and with the danger of injuring the same or of clogging or otherwise harmfully effecting said pens or the like reduced to a minimum. The sponge-rubber material, because of its easy exchangeability, is repeatedly available and is easily cleaned by washing.

Having thus described my improved pen-cleaner of sponge-rubber, it will be seen, that it has many advantages over those theretofore in use. Its cost is very little including the sponge and it is very durable.

I claim as my invention:

1. A pen-cleaner comprising a pair of elements lying in surface engagement with each other, at least one of said elements being of sponge-rubber and means for resiliently fastening said elements together at an intermediate point whereby the surface engagement of said elements is maintained and the edges thereof are free and disconnected to permit a pen to be inserted between said elements and subjected to the cleaning action of the sponge-rubber.

2. A pen-cleaner comprising two arched plate-shaped parts having opposed convex

sides, sponge-rubber elements fixed upon said convex sides of the plate-shaped parts and an elastic member connecting said plate-shaped parts whereby a pressure toward each 5 other upon the peripheries thereof, at any point, causes said sponge-rubber elements to spread apart at a diametrically opposite point.

3. In a pen-cleaner, the combination of a 10 body having a receiving surface of predetermined shape, a covering of sponge-rub-

ber fitted upon the receiving surface of said body, and conformed to the shape thereof, and resilient means whereby said sponge-rubber covering is secured to said body. 15

In testimony whereof I affix my signature in presence of two witnesses.

JOSEPH MAY.
